UNITED STATES PATENT OFFICE.

LOAMMIE A. GUTRIDGE AND FRANK M. MOSIER, OF COLUMBUS, OHIO, ASSIGNEES, BY
DIRECT AND MESNE ASSIGNMENTS, OF ONE-THIRD TO SAID GUTRIDGE AND TWO-
THIRDS TO G. N. SLONAKER, OF COLUMBUS, OHIO.

SWITCH ATTACHMENT FOR FOLDING MACHINES.

Application filed January 20, 1921. Serial No. 438,547.

To all whom it may concern:

Be it known that LOAMMIE A. GUTRIDGE and FRANK M. MOSIER, citizens of the United States, residing at Columbus, in the 5 county of Franklin and State of Ohio, have invented certain new and useful Improvements in Switch Attachments for Folding Machines, of which the following is a specification.

10 This invention relates to an improved switch attachment for paper folding machines of the type utilized in printing establishments for the purpose of folding printed sheets into pamphlets or book 15 leaves, the object of the invention being to provide means in conjunction with such a machine, whereby in the event of the paper becoming clogged or unduly stopped in the passageways or paper guides thereof, means 20 will be actuated to automatically stop the driving motor of the machine and to thereby discontinue its operation until the clogging materials have been removed from their obstructing positions.

25 In the operation of paper folding machines, considerable loss has heretofore been occasioned by the failure of the paper sheets passing therethrough to properly conform and follow the guides of the machine. Fre- 30 quently, these guides are formed to provide narrow restricted openings through which the paper sheets are allowed to pass, and therefore in the event of the failure of a sheet to properly pass through an opening 35 of this nature, the latter has become clogged by the paper disposed therein, with the result that following sheets are also prevented from passing through the machine until the clogging sheets have been removed. Ordin- 40

narily, the operator of the machine is not instantly aware of the stoppage, and it is not until after a number of sheets have been passed through the machine that the defect therein is noted. This clogging of the ma- 45 chine, therefore, results in considerable loss of paper and in the time of the operator which is used in overcoming the difficulties presented. Inasmuch as this condition is present many times a day, during the opera- 50 tion of the machine, it is patent that consider- able loss from a standpoint of mate- rials and also of time consumed in effecting repairs is present. In order to obviate these difficulties, and others, the present inven-

tion consists in the provision of a switch 55 mechanism, which is adapted to be positioned in one or more of the paper guides of a folding machine, said switch mechanism being normally out of the path of movement of the paper sheets through the 60 guides, but so positioned that when the guide adjacent thereto has become clogged, the collection of paper therein will effect the closing of a circuit governed by the switch mechanism, which circuit results in 65 controlling a motor circuit, in which the driving motor of the machine is located, whereby said motor circuit will be opened to instantly arrest, in a purely automatic 70 manner, the operation of the machine, there- by notifying the operator of the clogged condition of the machine and to permit the steppage to be readily overcome in a simple and convenient manner, since the stoppage is of a relatively simple nature and can be 75 easily removed, when the switch mechanism is operated.

For a further understanding of the invention, reference is to be had to the following description and to the accompanying drawings, in which similar characters of reference denote like and corresponding parts throughout the several views thereof.

In said drawings:

Figure 1 is a plan view of a portion of 85 the structure of a paper folding machine, and illustrating more particularly the application of the switch attachment comprising the present invention thereto.

Figure 2 is a horizontal sectional view 90 taken on the line 2—2 of Figure 1, and.

Figure 3 is a diagrammatic view disclosing the circuits connected with the switch mechanism.

In the form of the invention disclosed in 95 the accompanying drawings, the numeral 1 designates the frame of an ordinary conventional form of a paper folding machine. As usual, this machine is formed to include a paper guiding structure, which in the pres- 100 ent instance consists of a pair of vertically disposed folding rolls 2, between which paper sheets may be passed and suitably bent in any desired folded order. Also, in the present disclosure, the frame 1 is provided 105 with a pair of parallel vertically extending shafts 3, carrying guide rolls 4, which rolls act to receive the paper sheets after the lat-

ter have been ejected from the folding rolls 2, and to conduct the paper forwardly through guide strips 5. These guide strips are of the usual nature and are disposed in pairs, the same having certain of their side edges disposed in adjacent relationship, so as to provide a restricted guide opening 6 therebetween. It will also be noted that the strips 5 are located in rearwardly diverging order, whereby the same will be in position to receive the paper discharged from the rolls 4 and to permit said paper to be guided forwardly through the properly positioned opening 6. The paper is then carried on past a guide member 7, and is engaged with vertically disposed rolls 8, which are mounted for rotation on horizontal shafts. These latter rolls serve to engage the paper received therebetween, and to conduct the paper laterally to other contiguous and adjacent folding mechanism. From the foregoing it will be understood that the paper is initially delivered to the rolls 2 and is folded in any suitable manner by the latter. After passing from the rolls 2, the paper is delivered to the guide rolls 4, which draws the paper onwardly through the guide opening 6. The diverging strips 5 serve to receive the paper irrespective of its position of discharge from the rolls 4, and to direct said paper toward and through the opening 6. From this opening the paper is carried onwardly by the rotating rolls until the same engages with the vertical rollers 8, which as above stated convey the paper toward the discharge end of the machine or to adjacent folding members.

It repeatedly happens in the operation of a machine of this character, that the paper passing from the rollers 4 will be caught or wedged into the space defined between the strips 5, and when so caught or wedged, the paper clogs and can not pass through the outlet opening 6. Thus, an obstructing sheet of paper between the strips 5 will serve to arrest the onward movement of succeeding sheets, with the result that in a short time the space between the guide strips is completely filled with the clogged sheets, so that the operation of the machine is prevented. This clogging results in considerable inconvenience in effecting the removal of the clogging materials, in the complete loss of the sheets so caught, which become wrinkled and torn, in the stopping of the machine and in the loss of time required to effect suitable repairs.

To avoid this condition, the present invention consists in providing a switch attachment 9, which is preferably formed from an insulating material and comprises a U shaped body 10, having an inner wall 11 and a spaced outer wall 12. The outer wall is equipped with a set screw 13, whereby the attachment may be positioned upon one

of the strips 5 in the manner shown in Figure 2, and then securely held in such applied position by means of the friction exercised through the medium of the screw 13. The body is also formed to include a resilient contact 14 and a stationary contact 15, both of which being situated adjacent to the inner wall 11 of the body. However, the normal resiliency of the contact 14 maintains the latter spaced from the contact 15, so that a circuit connected with these contacts will normally remain open. These contacts are provided with spaced binding members 16, which are normally insulated from each other to prevent short circuiting through the attachment.

Leading from the binding member of the stationary contact is a wire 17, and leading from the binding member of the resilient contact is a companion wire 18. The wire 18 leads to a wire 19, which is situated so as to connect the windings of a rheostat 20 with a magnet 21, from which a return wire 22 extends, the latter being connected as at 23 with the wire 17. The motor 24 employed for operating the movable parts of the folding machine is connected with an incoming lead 25, and from the motor a wire 26 is extended to the movable circuit controlling handle 27 of the starting switch or rheostat. It will be manifest that by rotating the handle 27 toward the rheostat windings, current will be permitted to enter the motor of the lead 25, and the circuit will be continued through the wire 26 to the handle 27, through the wire 19 and the magnet 21, causing the latter to be energized, and from the magnet 21 to the source of current supply by way of the return wire 22. It will of course be appreciated that by virtue of this construction, the position which the handle 27 will assume with relation to the rheostat windings will control the quantities of current passing through the motor 24, and that by moving the handle 27 to an extreme position, the motor circuit will be broken altogether.

As is usual in this class of devices, the handle 27 is provided with a ratchet face 28, with which a movable detent or armature 29 is adapted to engage. The armature operates with the magnet 21, so that when the latter is energized, said armature will be revolved about its pivot into engagement with the ratchet teeth 28, thereby holding the handle 27 against movement, and preventing the operating spring 30 of said handle from revolving the latter to a circuit opening position. When the circuit through the magnet has been broken, it will be manifest that said armature will respond to the influence of its spring 31, so that the same will be released from engagement with the handle 27. When this release is effected the spring 30 of the handle 27 will return

the latter to a neutral position, thereby opening the circuit. This form of starting switch is common in mechanisms of this character and hence no claim is made on the same by itself, the present invention residing in associating the attachment 9 with the starting switch circuits in such manner that the motor 24 will be stopped automatically.

In operation, the handle 27 is rotated so that the motor circuit will be closed, thereby energizing the motor and effecting the consequent operation of the folding machine, which operation includes the rotation of the rolls 2, 4 and 8. During the operation of the rolls, paper will be forced between the guide strips 5 without engaging normally the switch attachment. However, in the event that the opening 6 or its equivalent becomes clogged with twisted paper, pressure will be applied to the resilient contact 14 by the crowding of the paper between the strips 5, with the result that the contacts 14 and 15 will be engaged, thereby short circuiting the magnet 21, so that the latter will be de-energized. This results in releasing the engagement between the handle 27 and the armature or detent 29, thereby causing the handle 27 to be rotated to a neutral position, by the influence of its spring 30, an operation which results in the opening of the motor circuit. When the motor circuit is opened, the motor is thereby stopped causing discontinuance in operation of the folding machine, thereby notifying the operator of the clogged condition of the machine and also enabling such condition to be eliminated. The strips 5 are readily removable from attachment with the frame 1, and hence access between the same may be readily reached.

In view of the foregoing description, it will be apparent that the present invention provides a simple and efficient attachment for the purpose set forth, and one which may be quickly applied to present standard equipment and which will positively operate to the operation of the folding machine after the latter has become clogged in any manner by the passing of paper therethrough.

While the foregoing description specifically sets forth what is now believed to be the best mode of applying the principles of the invention, yet it should be understood that such description does not necessarily measure the invention except as the latter is defined by the following claims.

What is claimed is:

1. In a paper folding machine, in combination, a guide structure for directing paper through said machine, a switch attachment comprising inner and outer walls adapted to detachably engage therebetween a part of the guide structure, said attachment being positioned so that a circuit therethrough will be closed when paper is clogged within said guide structure, a motor for operating said machine, a starting switch for said motor, and circuit connections between said starting switch and said switch attachment, whereby upon the closing of the circuit governed by said switch attachment, said motor switch will be opened to arrest current flow through said motor.

2. In a paper folding machine, in combination, a guide structure operable to govern the path of paper travel through said machine, a switch cooperative with said guide structure and positioned so as to be normally out of the path of paper travel through the guide structure, said switch comprising inner and outer walls for detachably engaging therebetween a part of the guide structure, stationary and movable contacts on the inner wall of the switch so that when said guide structure is clogged pressure will be brought to bear upon one of said contacts to bring them into engaged relation, means carried by the outer wall of the switch for clamping the switch to the guide structure, a motor, and a circuit for said motor and switch, whereby upon the engaging of said contacts current flow through said motor will be arrested.

In testimony whereof we affix our signatures.

LOAMMIE A. GUTRIDGE.
FRANK M. MOSIER.
